OXIDIZING BATHS CONTAINING PERCHLOROFLUOROCARBOXYLATES

William E. Hanford, Short Hills, N.J., assignor, by mesne assignments, to Minnesota Mining and Manufacturing Company, St. Paul, Minn., a corporation of Delaware

No Drawing. Application September 22, 1955
Serial No. 536,011

4 Claims. (Cl. 252—186)

This invention relates to the use of perchlorofluorocarboxylic acids, or salts thereof, having from about 4 to 20 carbon atoms as surface active agents in bleaching processes.

In the paper industry there is great difficulty involved in bleaching wood pulp to a high permanent brightness without affecting the strength of the cellulosic material and the paper made therefrom. The bleaching solutions have the undesirable property of attacking cellulose and weakening it through chemical reaction and depolymerization, as determined by viscosity measurements.

In the textile industry a careful control is kept of bleaching conditions in order that a satisfactory bleach is accomplished with the least amount of deleterious action on the fibers. Most of the textile materials are sensitive to bleaching action, hence a strict control of bath temperature, time of immersion, pH and the concentration of bath constituents is maintained.

The various fibers each have their own processing peculiarities. In the scouring, desizing and processing of fibers of vegetable origin, there are natural color bodies, waxes, pectins and sizings which make the fabrics water repellent and thus tend to interfere with bleaching and dyeing.

In bleaching fabrics that are dyed in some portions there is the problem of staining due to crocking or due to dye that has washed out of the goods, hence it is necessary to use a dye conditioning agent. Goods composed of fibers of cellulose and artificial silks that contain colored portions dyed with naphthol and related dyes are not normally fast to active oxygen bleach solutions. The dye loses its original shade, brightness and luster and appears dull.

Photographic bleaching baths are used in multicolored photography for the bleaching of the silver image following color-forming development. In the processing of multicolor reversible film and multicolor negative film, the silver present in all the layers following development is converted into a salt by means of a bleaching bath, and the silver salt thus formed is removed by dissolving it in a solvent for the silver salt e. g., hypo. Certain color photographic emulsions contain an organic solvent for color-couplers, such as a water insoluble but water permeable cellulose binder or a high boiling crystalline material, and there is a tendency for these solvents to occlude the metallic silver following development and to prevent its conversion into a silver salt by the customary bleaching bath. The coupler originally present in the emulsion layer and the dye formed from it are dissolved in the organic solvent where the particles of metallic silver which are formed during the development step are enclosed so that they can no longer be affected by the bleaching bath. Unremoved silver causes a haze, a poor color rendition and has a deteriorating action upon the layers in which it is located with the result that the picture is obliterated.

In the bleaching of wood pulp, the bleaching systems

2

have a single step, two steps or multiple steps, and these general types of bleaching use different bleaching chemicals or combinations of them. Probably the most satisfactory of the known bleaching methods is a multiple 5 step system where the pulp is exposed to the action of chlorine or a hypochlorite in one or more steps, followed by a caustic extraction stage in which some solubles are removed. Finally, there are one or more bleaching stages. The pulp can be in a slurry or in the form 10 of a sheet or a wet web.

In the textile industry bleaching is performed on animal fibers such as wool and silk, on vegetable fibers such as cotton and linen, on artificial fibers such as rayon and nylon, in the form of raw stock or carded, spun, 15 woven, knitted or felted as a fabric. The practical conditions are a scouring with washing and rinsing, followed by bleaching either in a bath or by other means of contact. When the bleaching is completed in one or several treatments, the excess liquid is removed by rollers or 20 some other device and the material is washed and dried.

The surface active agents used in this invention can be incorporated in the bleaching of wood pulp, cellulose ethers, cellulose esters and other cellulose derivatives, 25 nylon, rayon and other synthetics, starches, sugars, sponges, walnut shells and other nut shells, shellac and other resins, oils, fats, waxes, soaps, fatty acids, petroleum derivatives, multicolored photographic films, silk, wool, cotton, linen and the other materials susceptible to bleaching.

In some bleaching processes there is the problem that the bleaching effect is not stable and is subject to retrogression or degradation with lapse of time. It is known that bleaching accomplished by the use of reducing or deoxidizing agents is subject to the defect of being transitory, i.e., upon subsequent exposure to air the material 30 reverts to the original color and the bleaching effect is lost.

As a means of insuring bleaching in an economical and practical manner, control of surface tension by the use of 40 surface active agents has been attempted. The best of these surface active agents include aliphatic alcohol sulfates, aliphatic sulfonates, alkylated aromatic sulfonates, aliphatic ketones and alcohols, phenoxy alcohols, sulfonated-dicarboxylic acids, sulfonated oils, derivatives of pyridine bases, mixtures of phenols and hydrogenated phenols, and various mixtures consisting of organic solvents and wetting agents. Most of the surface active 45 agents have limited use in bleaching operations. It is known that when oxidizing compounds are mixed with organic materials the constituents tend to decompose. Heretofore, the use of wetting agents has been limited to dilute solvents to avoid formation of unstable mixtures. Surface active agents suitable for use in bleaching processes must be resistant to oxidation and/or hydrolysis 50 in acidic and basic media. They must not cause excessive decomposition of the active bleach component, and they must be capable of increasing the penetrating, emulsifying or dispersing properties of the solvents. Also, their 55 presence must not affect the important physical characteristics of the immersed material.

The ordinary surface active agents have not been found satisfactory for use under corrosive conditions. They are subject to decomposition or to alteration in structure. They lose their effectiveness as surface active agents and sometimes lead to undesirable bath properties. They cannot be mixed in concentrated bleach mixtures for storage or shipping purposes because there is a rapid decomposition of components which can assume 60 dangerous proportions.

The surface active agents used in this invention help solve many of the aforementioned problems. The perchlorofluorocarboxylic acids and salts increase the prob-

ability that surfaces will be uniformly wetted and acted upon by the bleaching solution and the surfaces are more effectively cleansed of contamination and foreign matter that interfere with the bleaching action. In processes using high temperatures the surface active agents act to reduce spray, splash and mist through the lowering of the surface tension; also, the drag-out losses are reduced thereby conserving both the bath constituents and the surface active agents. Further, there is no loss of surface active agents due to chemical decomposition or reaction, and there are no deleterious effects on the bleaching solution or material immersed therein because of a transformation of the surface active agent compounds.

These surface active agents also shorten the time necessary for a proper bleach by increasing the wetting and penetrating power of the solution, thereby avoiding long and drastic bleaching. In multiphase bleaching systems, i.e., oils, fats, waxes, and the like, in aqueous mixtures, the lowering of the surface and/or interfacial tension increases the bleaching rate markedly. The shorter immersion time helps prevent excessive decomposition or depolymerization of the particular material in the process. Also, the surface active agents permit a broader range of temperature and pH, thereby allowing a wider choice of the most favorable conditions.

Another important result of the use of perchlorofluorocarboxylic acids and salts thereof as surface active agents in bleaching processes is that smaller amounts of expensive bleach agent, e.g., hydrogen peroxide, are required to obtain a necessary degree of bleaching when the surface active agent is present. Further, these surface active agents can be included in concentrated mixtures which are stored or shipped for use as bleaches, disinfectants, germicides or deodorants and which normally are not safe with some ordinary surface active agents. The mixtures may be dry, or in a solvent to form a liquid, cream or paste.

Other benefits derived from the use of these surface active agents in bleaching processes are dependent on the particular bleaching agents, materials and processes involved. These surface active agents can have a stabilizing effect on the active components of the bleaching mixture and this can be of significance where the bleaching is accomplished in acid media. Acid bleach is generally unsatisfactory because of deterioration of the bleaching solution and of the product. The surface active agents can make acid bleaching practical by stabilizing the solution and by preserving the product through shorter immersion time.

The perchlorofluorocarboxylic acid surface active agents can be used successfully in combination with most bleaching reagents including sulfur dioxide, sulfuric acid, sulfites, bisulfites, hydrosulfites, chlorine, chlorites, hypochlorites, peroxides, persulfates, perborates, percarbonates, persilicates, permanganate, ozone, aqua regia, alkali metal ferricyanides, sulfur dioxide, and the like, with or without stabilizing agents such as sodium silicate, caustic soda, soda ash, or the like, or other agents or compounds such as epsom salts, formaldehyde, phenoxy alcohols, catalytic salts, e.g., cobalt and nickel chlorides, sulfates or nitrates, and the like, which give beneficial effects when incorporated in certain bleaching mixtures.

In hot, highly agitated bleaching baths the amount of frothing can be controlled with the surface active agents and there is less need for a cold water spray.

The perchlorofluorocarboxylic acids which can be used are prepared in a variety of ways. For example, they may be produced by subjecting perhalogenated aliphatic olefins, having at least 7 carbon atoms and being at least half fluorinated, to oxidation conditions in the presence of a vigorous oxidation reagent, such as free oxygen in the presence of ultraviolet light, free oxygen in the presence of ultraviolet light and elemental chlorine, free oxygen in the presence of elemental fluorine, and permanganate salts in a liquid medium. Preparation of the acids according to this method is disclosed in copending

application Serial No. 452,706, filed August 27, 1954.

The acids also may be prepared by subjecting aliphatic perhalogenated high polymers to thermal cracking conditions to produce lower molecular weight materials having molecular weights in the oil or wax range and subjecting these materials to oxidation at a temperature not higher than about 10° C. in the presence of a permanganate salt in a liquid medium. Processes of this type are disclosed in copending application Serial No. 452,704, filed August 27, 1954.

Also, the perchlorofluorocarboxylic acids used in this invention may be prepared by heating fluorine-containing telomers, having the general formula,

in which R is a perhalomethyl radical having a total atomic weight not higher than 146.5, X₁ and X₂ are fluorine or chlorine atoms, and n is an integer from 2 to 16, with fuming sulfuric acid at a temperature of at least 125° C. This process produces carboxylic acids having the formula,

in which Z is a carboxylic acid radical or a perhalomethyl radical having a total atomic weight not in excess of 146.5 and n is an integer from 2 to 16. The preparation of these acids is disclosed in copending application Serial No. 452,703, filed August 27, 1954, now Patent No. 2,806,865.

The preferred process for the preparation of perchlorofluorocarboxylic acids useful in the process of the present invention is the hydrolysis of telomers produced by telomerizing perhaloolefins using sulfuryl chloride as a telogen. The hydrolyzed telomer has the formula,

in which Z is a carboxylic acid radical or a perhalomethyl radical in which all the halogen atoms are fluorine or chlorine and n is an integer from 2 to 16. The preparation of these acids is disclosed in copending application Serial No. 452,705, filed August 27, 1954, now Patent No. 2,806,866.

The perchlorofluorocarboxylic acid salts which may be used in the present invention are those disclosed in copending application Serial No. 501,782, filed April 18, 1955, now Patent No. 2,806,867, the preferred salts having the formula,

in which Z is chlorine or a perhalomethyl radical having a total atomic weight not in excess of 146.5, n is an integer from 2 to 10, x is an integer from 1 to 4 and M is a metal or ammonium cation.

The surface active agents can be used in amounts ranging from 0.01 gram to 10 grams/liter and at temperatures from freezing up to 250° C.

The invention will be further illustrated by reference to the following specific examples:

Example 1

Carboxyethyl cellulose (1 kg.) is slurried in 87 percent isopropanol and neutralized to a pH of 7 with phosphoric acid. The mixture is heated to 60° C. and treated with sodium chlorite solution (1 gram of a 25 percent aqueous solution with 6 percent available chlorine) and 0.3 gram of the potassium salt of

The slurry is agitated for 15 minutes then filtered, washed with methanol and water, and air dried.

Example 2

A fish oil (500 grams) is emulsified by the addition of water. After the addition of 200 ml. of a 3 percent aqueous hydrogen peroxide solution and 0.5 gram of the

potassium salt of $\text{Cl}(\text{CF}_2\text{CFCl})_3\text{CF}_2\text{COOH}$, the system is boiled for 10 minutes. Frothing is controlled by the amount of surface active agent added or by the use of a cold water spray if necessary. The system is cooled and the oil is separated and washed.

Example 3

Wood pulp is fed to a forming machine to produce a sheet which is dewatered and treated with a quantity of hydrogen peroxide solution sufficient to give the brightness desired (0.2-1.0 percent of H_2O_2 based on dry weight of pulp). One gallon of the bleaching solution contains 0.5 pound of 27.5 percent hydrogen peroxide, 1.5 pounds of sodium silicate, of 42° Bé. gravity, and 1 gram of the potassium salt of $\text{Cl}(\text{CF}_2\text{CFCl})_3\text{CF}_2\text{COOH}$.

The impregnated sheet is shredded and transferred to a retention tower for 30 minutes to an hour, depending on the extent of color improvement needed. The pulp is then discharged into a suitable apparatus for neutralization and dilution to produce a stock from which paper can be made.

Example 4

1500 grams of commercial sorbitan monostearate is stirred at a temperature of 75° C. and treated with 5 grams of sodium chlorite (50 percent aqueous solution) and 0.5 gram of a salt of $\text{Cl}(\text{CF}_2\text{CFCl})_3\text{CF}_2\text{COOH}$ for 30 minutes. The mixture is concentrated under vacuum and filtered with dilute alcohol washing.

Example 5

A soft wood kraft pulp is treated with 8 percent hypochlorite bleach at 8 percent stock density at 25° C. for one hour and then diluted to 40 percent stock density with sufficient chlorine water to give 2.5 percent chlorine, based on the weight of dry pulp, and is allowed to stand for one hour at room temperature; it is then washed, antichlored with SO_2 water and rewashed.

In a second stage, the pulp is subjected to a hot caustic treatment with 1.5 percent sodium hydroxide at 15 percent stock density for two hours at 78° C. and then washed.

As a final stage, the pretreated pulp is bleached with 1 percent chlorine dioxide, based upon the dry weight of the pulp, for one hour and a half at 70° C. and a pH 5.8 in the presence of 0.3 gram/gallon of the potassium salt of $\text{Cl}(\text{CF}_2\text{CFCl})_3\text{CF}_2\text{COOH}$. This is followed by washing, antichloring and final washing.

Example 6

100 pounds of toweling dyed, in portion, with a naphthol dye is treated at 100° C. for four hours with 50 gallons of a solution containing 500 grams of hydrogen peroxide, 500 grams of sodium silicate (40° Bé.), 200 grams of epsom salts and 15 grams of the potassium salt of $\text{Cl}(\text{CF}_2\text{CFCl})_3\text{CF}_2\text{COOH}$. The material is then washed and dried.

Example 7

A piece of acetate rayon fabric weighing 100 grams is immersed in a solution containing 500 ml. of aqueous sodium chlorite (25 grams of available chlorine), 1 liter

of pH 7 phosphate buffer solution, 400 ml. of a dilute solution of formalin containing 5 grams of formaldehyde and 0.5 gram of the potassium salt of

The mixture is heated for one hour at 50° C., then washed and dried.

It will be obvious to those skilled in the art that many modifications may be made within the scope of the present invention without departing from the spirit thereof, and the invention includes all such modifications.

I claim:

1. An aqueous oxidizing bath containing between about 0.01 and about 10 grams per liter of a water soluble substance selected from the group consisting of alkali metal and ammonium salts of a compound having the formula

in which Z is selected from the group consisting of chlorine and perhalomethyl radicals having a total atomic weight not in excess of 146.5, and n is an integer from 2 to 10.

2. An aqueous oxidizing bath containing between about 0.01 and about 10 grams per liter of a water soluble substance selected from the group consisting of alkali metal and ammonium salts of a compound having the formula

in which n is an integer from 2 to 10.

3. An aqueous oxidizing bath containing between about 0.01 and about 10 grams per liter of a water soluble compound having the formula

in which Z is selected from the group consisting of chlorine and perhalomethyl radicals having a total atomic weight not in excess of 146.5, n is an integer from 2 to 10, x is an integer from 1 to 4, and M is an alkali metal.

4. An aqueous oxidizing bath containing between about 0.01 and about 10 grams per liter of a water-soluble compound containing 4 to 33 carbon atoms selected from the group consisting of alkali metal and ammonium salts of a perchlorofluorocarboxylic acid.
